W. H. HIGGINS.
METAL RAILWAY TIE.
APPLICATION FILED JUNE 20, 1912.

1,056,025.

Patented Mar. 18, 1912

UNITED STATES PATENT OFFICE.

WILLIAM H. HIGGINS, OF WASHINGTON, NEW JERSEY.

METAL RAILWAY-TIE.

1,056,025.

Specification of Letters Patent. Patented Mar. 18, 1913.

Application filed June 20, 1912. Serial No. 704,855.

To all whom it may concern:

Be it known that I, WILLIAM H. HIGGINS, a citizen of the United States, residing at Washington, in the county of Warren and 5 State of New Jersey, have invented certain new and useful Improvements in Metal Railway-Ties, of which the following is a specification.

This invention relates to improvements in 10 metal railway ties, and has for one of its objects to improve the construction and increase the efficiency and utility of devices of this character.

Another object of the invention is to provide 15 a metal railway tie cast in one piece throughout and provided with rail-supporting members of non-conductive material, to act as insulators to the rails when the tie is employed in electric railway lines.

Another object of the invention is to provide 20 a tie having a novel means for holding rail-supporting blocks and preventing the latter from movement in any direction relative to the tie or the rail.

Another object of the invention is to provide 25 ties having means for maintaining the same in uniform and permanent spaced relations.

Another object of the invention is to provide 30 a tie having rail-supporting blocks connected thereto and held from movement in all directions relative to the tie and means for locking the blocks to the tie, and taking up "slack" in event of the shrinkage of the 35 block.

With these and other objects in view, the invention consists in certain novel features of construction as hereafter shown and described, and then specifically pointed out in 40 the claims, and in the drawings illustrative of the preferred embodiment of the invention: Figure 1 is a side elevation of one of the improved ties with a pair of rails supported thereon and in transverse section; Fig. 2 is a plan view of the same; Fig. 3 is 45 an end elevation of one of the improved ties; Fig. 4 is a transverse section on the line 4—4 of Fig. 1; Fig. 5 is a perspective view of one of the end portions of the improved tie; Fig. 6 is a detached perspective view of one of the spacer bars.

Corresponding and like parts are referred to in the following description and indicated in all the views of the drawings by the 55 same reference characters.

The improved tie is constructed from cast

metal, preferably steel, and comprises a base having relatively wide end portions 10 and a reduced central connecting web portion 11, the reduced connecting portion being curved upwardly intermediate its ends as represented in Fig. 1, to enable a portion of the "tamping" to be disposed beneath the curved portion and thus effectually prevent longitudinal "creeping" of the tie. The 60 lateral reduction of the tie likewise enables the tamping material to be embedded between the widened ends 10 which also assists in preventing the longitudinal creeping. The flat end portions 10 and the curved web portion 11 are preferably of the same thickness and for an ordinary tie will be about $1\frac{1}{4}$ inches thick, but these dimensions may be varied as preferred.

Rising from each of the widened end portions 10 are bearing standards 12—13 spaced apart and extending at a slight oblique angle to the longitudinal plane of the tie and extending partly across the portions 10 of the same as shown in Fig. 2. The 70 standards are arranged in pairs and one pair is located near each end of the tie, as shown. The standards 12—13 are likewise converged toward their upper ends, and are coupled by an integral closing plate 20 75 at one side, as shown, and spaced below the upper line of the standards, and likewise spaced above the base. Bearing between each pair of the standards, is a rail-supporting block 14 preferably of wood or like material, and bearing upon the tie between the standards, and against the closing plate. By this simple means the block is held from upward movement by the converging form of the standards and from movement in one 90 direction by the plate 20 and can be moved laterally in one direction only and at an oblique angle to the longitudinal plane of the tie, the object to be hereafter explained.

The body portions 10 of the tie are connected to the standards by bracing webs 15 and the material of the tie between the braces is thickened as illustrated at 16, to increase the strength and to form additional bracing means against the standards.

The standards are each provided with obliquely extending recesses 17 directed inwardly and downwardly from their upper outer corners to receive wedge blocks 21 which when driven into the recesses engage 110 against the blocks 14 and are partly embedded therein and thus lock the latter firmly.

in position between the standards. The rails, represented conventionally at 18, rest upon the blocks 14, and are secured in place thereon by clamp bolts 19 or like fastening devices. By constructing the blocks 14 of wood the rails are insulated from the ties which will be a necessity when the improved tie is employed in electric railway lines, as will be obvious. The rails 18 being rigidly secured to the blocks 14 and at right angles to the longitudinal plane of the tie, firmly hold the blocks from movement between their standards and likewise hold the ties from lateral "creeping" as will be obvious. As the blocks are firmly connected by the bolts 19 to the rails and also firmly held from movement laterally of the ties by the oblique and converging arrangement of the standards, it will be obvious that all tendency of movement between the rails and the tie and the blocks, is effectually prevented.

Formed upon the side faces of the brace portions 15 are small pockets or sockets 22 to support the ends of spacer bars 23, which thus serve to maintain the ties spaced permanently at uniform distances apart.

The improved device is simple in construction, can be cheaply manufactured and employed in any locality where ordinary railway ties are required.

The improved device may be embedded in the tamping or ballast of the road bed, or attached to a sub-tie or base by bolts or other fastening devices, or connected to the stringers or other like portions of bridges, trestles, elevated railway supports or the like.

Having thus described the invention, what is claimed as new is:

1. A railway tie comprising a base having standards rising therefrom and arranged in pairs, said standards being extended obliquely to the longitudinal axis of the base and in parallel relations, and a rail-bearing block located upon the base between each pair of standards.

2. A railway tie comprising a base having standards rising therefrom and arranged in pairs, said standards being extended obliquely to the longitudinal axis of the base and in parallel relations, and a

rail-bearing block of insulating material located upon the base between each pair of standards.

3. A railway tie comprising a base having standards rising therefrom and arranged in pairs, said standards being extended obliquely to the longitudinal axis of the base and in parallel relations and converging toward the upper ends, and a rail bearing block located upon the base between each pair of standards.

4. A railway tie comprising a base having standards rising therefrom and arranged in pairs, said standards being extended obliquely to the longitudinal axis of the base and in parallel relations, a rail-bearing block located upon the base between each pair of standards, and means for locking said blocks to the standards.

5. A railway tie comprising a base having standards rising therefrom and arranged in pairs, said standards being extended obliquely to the longitudinal axis of the base and in parallel relations, a rail-bearing block located upon the base between each pair of standards, and braces between the standards and the base.

6. A railway tie comprising a base having standards rising therefrom and arranged in pairs, said standards being extended obliquely to the longitudinal axis of the base and in parallel relations, and with oblique key seats in their inner faces, a rail-bearing block located upon the base between each pair of standards, and locking keys engaging in the keyways and bearing against the blocks.

7. A railway tie comprising a base having standards rising therefrom and arranged in pairs near the ends and reduced and curving upwardly intermediate the standards, said standards being extended obliquely to the longitudinal axis of the base and in parallel relations, and a rail-bearing block located upon the base between each pair of standards.

In testimony whereof I affix my signature in presence of two witnesses.

WILLIAM H. HIGGINS. [L.S.]
